Application December 30, 1939, Serial No. 89,246

Term of patent 14 years

To all whom it may concern:

Be it known that we, Albert W. Scarratt, Raymond Loewy, and William H. Harstick, citizens of the United States, residing at Kenilworth, in the county of Cook and State of Illinois; New York, in the county of New York and State of New York; and, Richmond, in the county of Wayne and State of Indiana, respectively, have invented a new, original, and ornamental Design for a Cream Separator, of which the following is a specification, reference being had to the accompanying drawing, forming part thereof, in which:

separator, showing the cream and milk spouts from the side;

Figure 2 is a side perspective view, showing the cream and milk spouts from the front; and,

We claim:

The ornamental design for a cream separator, as shown.

ALBERT W. SCARRATT.
